US0D1075731S

(12) **United States Design Patent** (10) **Patent No.:** **US D1,075,731 S**
(45) **Date of Patent:** **** May 20, 2025**

(54) **ANTENNA**

(71) Applicant: **Autel Robotics Co., Ltd.**, Guangdong (CN)

(72) Inventor: **Boming Lu**, Guangdong (CN)

(73) Assignee: **Autel Robotics Co., Ltd.**, Guangdong (CN)

(**) Term: **15 Years**

(21) Appl. No.: **29/923,503**

(22) Filed: **Dec. 29, 2023**

(51) LOC (15) Cl. **14-03**

(52) U.S. Cl.

USPC **D14/230**

(58) **Field of Classification Search**

USPC D14/230, 231-240, 138, 358, 124, 137, D14/299, 238.1; D12/42, 32, 43; D13/168, 192

CLAIM

The ornamental design for an antenna as shown and described.

DESCRIPTION

FIG. 1 is a front, right and top perspective view of an antenna, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the antenna that form no part of the claimed design.

1 Claim, 8 Drawing Sheets
